UNITED STATES PATENT OFFICE

OTTO SIEMEN AND JOHANNES HINSCH, OF ITZEHOE, HOLSTEIN, GERMANY

ROTARY PUMP

Application filed March 7, 1928, Serial No. 259,799, and in Germany June 22, 1927.

When a rotary pump is employed for exhausting the air from siphonic conduits or from the suction pipes of pumping plants and the like, it is usual to provide a valve in the piping leading from or to the exhauster pump so that said piping can be closed in order to render the pump inactive as soon as it begins to draw liquid. This valve is operated by hand and must be constantly attended to, since the services of the pump may at any time be required.

The object of the present invention is to obviate the necessity of attending to the valve, and the invention consists in the combination with a rotary pump of the kind operating by means of a circulating liquid, of means whereby a stop cock is automatically opened and closed under the influence of the pressure variations in the pump due to the absence or presence therein of air.

To obtain this result, the cock is controlled by a lever and by a piston arranged in a cylinder which communicates with the pump casing.

The invention is illustrated in the accompanying drawing which represents a sectional view of the arrangement.

The cylindrical pump casing *a* contains an eccentrically disposed, vaned wheel by the rotation of which and by means of an auxiliary liquid which circulates along the circumference of the casing air or liquid is sucked in through a port *h* and discharged through a port *i*. The pump is connected through the port *h* which the siphonic conduit or other element which is to be kept clear of air. In the arrangement shown, a stop cock *b* is arranged in the pressure pipe of the pump, and the plug is connected by a lever arm and a link to a piston *d* arranged in a cylinder *c*. The latter communicates through an aperture *e* with the pump casing *a*, said aperture being situated in the side of the casing below the rotor and sufficiently near the latter to be swept by the vanes, i. e., in the region where the air, if present, will be maintained by the auxiliary liquid. The piston carries a weight *g* and may in addition be controlled by a spring *f* acting on the lever arm of the cock plug so as to retain the latter normally

in open position. The port *i* is comparatively small, however, and as soon as the pump begins to draw liquid, the port is incapable of discharging the latter at the same rate as that at which it is impelled by the rotor. 55 Thus the pressure in the casing *a* will be suddenly increased, and the increased pressure will be communicated through the port *e* to the cylinder *c* for raising the piston *b* and closing the valve. As long as the water pressure persists, the valve remains closed, but as soon as air enters the induction pipe, the water in the cells between the vanes flows back through the port *h* into the induction pipe and relieves the excessive pressure in the casing. The valve will then be reopened, and the air will be pumped out of the system. 60

The cock may be arranged at the suction side of the pump in which case, however, it is adapted to effect only an incomplete closure so that smaller quantities of air, admitted through leakage or the like, may be continually pumped through without any substantial discharge of liquid. For this purpose the cock plug may be provided with a small duct which opens when the normal plug aperture is closed. 75

We claim:

1. A rotary pump comprising a casing, a vaned wheel arranged eccentrically within the casing and sweeping the end walls and the top part of the circumference thereof, said casing having induction and exhaust ports situated in the end wall at opposite sides of the wheel axis and at the base of the vanes, the exhaust port being smaller than the induction port, a pipe communicating with the exhaust port, a valve in said pipe, an hydraulic controlling device for said valve tending to maintain the valve open, and a pipe connecting the controlling device with the pump casing through a port situated in the end wall of the casing below the wheel axis so as to be swept by the tips of the vanes, the controlling device being adapted to close the valve on an increase of pressure in the casing. 85

2. A device as claimed in claim 1 wherein the valve controlling device consists of a 90

spring-controlled piston and a cylinder for said piston.

3. A device as claimed in claim 1 wherein the valve consists of a cock plug and the controlling device, of a piston, a cylinder for said piston and a lever arm mounted on the plug and linked to said piston.

OTTO SIEMEN.
JOHANNES HINSCH.
